UNITED STATES PATENT OFFICE.

JOHN W. LANG, OF LOS ANGELES, CALIFORNIA.

CURTAIN-FIXTURE.

SPECIFICATION forming part of Letters Patent No. 552,870, dated January 7, 1896.

Application filed February 15, 1895. Serial No. 538,509. (No model.)

To all whom it may concern:

Be it known that I, JOHN W. LANG, a citizen of the United States, residing at Los Angeles, in the county of Los Angeles and State 5 of California, have invented new and useful Improvements in Curtain-Fixtures, of which the following is a specification.

My invention relates to those devices which are designed to allow the curtain to be lowered 10 from the top of the window to admit light through the upper part of the window and to screen the lower part of the window.

The object of my invention is to provide a device of this kind which will be neat and attractive in appearance, cheap and simple in construction, and effective and durable in operation; also to so construct the fixture that the strain of raising and lowering the curtain-roller will not in any way strain or 20 affect the bearings of the curtain-roller.

In my fixture the curtain-roller is suspended from a rod, which is carried by two keepers running on vertical guides or supports, and the keepers are supported by cords, which 25 are led over pulleys and sustained by weights inside the supports.

The accompanying drawings illustrate my invention.

Figure 1 is a front elevation of a window 30 provided with my invention, showing the curtain lowered from the top of the window and arranged to screen the lower part of the window. Fig. 2 is a fragmental sectional view of one of the tubular supports, showing the keeper in place upon the support and the weight arranged inside of the support.

My invention embraces a curtain-fixture comprising two parallel vertical tubular supports A A', arranged to be secured one upon 40 each side of the window at a distance from the face of the casing B; two keepers C C', arranged one upon each support and adapted to slide vertically therealong; two pulleys D D', one arranged at the top of each support; 45 two weights E E', one arranged to slide inside of each tubular support and to be concealed from view thereby; two flexible connections, such as the chains F F', one passing over each pulley E E' and each having its 50 ends respectively attached to its weight and keeper; a connecting-rod G arranged connecting the keepers with each other; two

brackets H H', secured upon the rod and arranged to receive a curtain I, which is thereby attached to the rod, and is thus carried by the 55 rod; two cords J J', secured respectively to the keepers, loosely looped and secured together midway between the keepers, and the counterbalancing-weight L secured to the cords at their point of attachment to counterbalance the weights E E' and to cause the 60 curtain I to remain where it is placed by the operator.

The curtain-brackets H H' are each provided with a collar h h', respectively, which 65 fit upon the rod G, and these brackets are thus adapted to be partially rotated upon the connecting-rod to carry the curtain I nearer to or farther from the window-casing B when desired. This movement of the brackets is 70 indicated in Fig. 2 by dotted lines.

The upright tubular supports are attached to the window-casing by means of lower and upper brackets K K', respectively. The upper bracket K' is provided with an outwardly-projecting pole rest or support k, which is 75 adapted to receive and support the curtain-pole for lace curtains. (Not shown.)

In order to provide means whereby to rigidly hold the keepers and to retain the rod G at 80 the upper end of the support when it is not desired to lower the curtain from the top of the window, I provide each support with a suitable catch M M' respectively arranged to project through the side wall of the tubular 85 support and to enter an annular channel e e', respectively provided in the bottom of the weights E E', thus to engage with the weights when the weights are in their lowest position to thereby prevent them from being drawn upward until the catches M M' are pulled outward by means of the knobs m m', and the weights are thus released.

The counterbalancing-weight L is just sufficiently heavy to cause such weight, the curtain and keepers and the connecting-rod to balance the weights E E', which are arranged within the tubular supports, and the friction of the various parts will cause the curtain to remain in any position in which it may be 95 when the weight L hangs free.

To lower the curtain, the cord or the adjusting-weight is grasped and pulled downward, thus causing the weights E E' to rise as the 100

curtain lowers. To raise the curtain, the adjusting-weight L is lifted and the weights E E' pull the curtain upward until the counterbalancing-weight is released and brings the various parts to rest. By attaching the cords to the lower parts of each keeper and bringing the cords together midway of the connecting-rod G when force is applied upon the counterbalancing-weight to pull the curtain down it operates equally upon each keeper, and I therefore avoid cramping the keepers upon the tubular supports and am enabled to readily move the keepers up and down therealong.

Since the curtain-roller is carried by the brackets which are attached to the connecting-rod, no strain is brought upon the curtain-roller by the act of raising or lowering the same. It is also possible by this construction to place the supports at a distance from the ends of the curtain, so that the curtain will always swing free from such supports and not be liable to strike thereagainst in case the curtain when run up should wind unevenly upon the roller and thus swing to one side, as sometimes occurs.

In practice my improved fixture is manufactured from polished metal, or is suitably plated, and when secured in place upon the casing forms a very neat and attractive ornament. The weights E E' or counterbalances for the curtain, which would be unsightly if exposed, are entirely obscured from view by means of the tubular casing. By means of the adjustable curtain-receiving brackets the curtain may be arranged to fit

as tightly against the window-casing as may be desired.

Now, having described my invention, what I claim as new, and desire to secure by Letters Patent, is—

1. A curtain fixture having an upright tubular support having at its top a pulley, a keeper arranged to slide along such support, a weight arranged to slide inside of the support, a flexible connection passing over the pulley and having one end secured to the weight and its other end secured to the keeper, and a suitable catch arranged to engage the weight when it reaches its lowest position.

2. A curtain fixture comprising two parallel vertical tubular supports arranged to be secured one upon each side of a window at a distance from the face of the casing; two keepers arranged one upon each support and to slide therealong; two pulleys, one arranged at the top of each support; two weights one arranged to slide within each support; two flexible connections one passing over each pulley and each having its ends attached to its respective weight and keeper; a connecting rod arranged connecting the keepers with each other; brackets secured to the rod and arranged to receive a curtain; a cord attached to each keeper pendent therefrom and secured together midway therebetween; and the counterbalancing weight secured to the cord.
